RESERVE GASOLINE TANK

Filed April 27, 1923

James A. Skaggs

By *Greene and Bond* Attorney

UNITED STATES PATENT OFFICE.

JAMES A. SKAGGS, OF CANTON, OHIO.

RESERVE-GASOLINE TANK.

Application filed April 27, 1923. Serial No. 635,026.

To all whom it may concern:

Be it known that I, JAMES A. SKAGGS, a citizen of the United States, residing at Canton, in the county of Stark and State of Ohio, have invented certain new and useful Improvements in Reserve-Gasoline Tanks, of which the following is a specification.

This invention relates to auxiliary fuel tanks and is especially adapted for use upon motor vehicles. The improvement has for its objects to provide a reserve fuel tank which may be easily connected to the usual vacuum feed system such as is commonly used upon automobiles, and which will be automatically filled by the operation of the vacuum feed tank, the reserve supply of gasoline being trapped in the reserve tank which may be called upon when the main supply carried by the vehicle is exhausted.

The above and other objects may be attained by constructing the device in the manner illustrated in the accompanying drawing, in which—

25 Figure 1 is a top plan view of a reserve tank embodying the invention, showing the action of the same to the vacuum feed system; and

30 Fig. 2, a vertical, sectional view through the reserve tank showing the vacuum feed mechanism in elevation.

Similar numerals refer to similar parts throughout the drawing.

The instrument board of an automobile is indicated at 1 and the vacuum tank 2, such as is commonly used in vacuum feed systems, may be connected thereto in the usual manner. Suction is created in the tank 2 by connecting the same to the intake manifold 3 in the usual manner as by the pipe 4.

45 The tube 4 is connected to the upper end of the vacuum tank 2 and a tube 5 is also connected to the upper end of the vacuum tank and leads to the main fuel supply tank from which the fuel is drawn by suction in the usual manner, to the vacuum feed tank. A pipe 6 is connected to the lower end of the vacuum feed tank and leads to the carburetor for the purpose of feeding the fuel thereto by gravity as is customary in these systems.

50 The reserve tank 7 may be supported by the curved brackets 8 connected to the instrument board as by the flanges 9, a bolt

10 drawing the brackets together between the tanks 2 and 7 and a bolt 11 connecting the flanged ends 12 of the brackets and clamping the reserve tank 7 therebetween.

A T 13 is provided in the pipe 5 between the main fuel supply tank and the tank 2 and connects with the upper end of the reserve tank 7. The lower end of the reserve tank may be provided with a drain aperture 14 normally closed by means of 65 the screw plug 15.

A tube 16 is extended through the central aperture 17 in the upper end of the reserve tank and has a flange 18 connected to its lower end, said flange being soldered or otherwise connected to the lower wall of the reserve tank. The threaded nipple 19 in the lower wall of the reserve tank registers with the tube 16 and receives the L 20 to which is connected the pipe 21, a T 22 75 being provided in the pipe 6, intermediate the vacuum tank and the carburetor for connecting the pipe 21.

One or more apertures 23 are provided in the tube 16 at a point spaced from the bottom of the reserve tank and a screen 24 surrounds the lower end portion of said tube, being connected thereto at a point above said apertures.

A rod or tube as shown at 25 is slidably mounted in the tube 16 and normally rests upon the upper end of the L 20 and as the same fits snugly within the tube 16, the apertures 23 are thus normally closed.

55 A wire 26 is connected to the upper end 90 of the tube 25 and leads through the tube 27 to the instrument board, being provided with an operating knob 28 upon its extremity and with a shoulder 29 near its outer end for engagement with the bracket 30. 95

A spiral spring 31 is located around the lower portion of the wire 26 and interposed between the washers 32 and 33, which are held in engagement with the tubes 25 and 27 respectively, by means of the spring. 100

The tube 25 is thus normally held in the position shown in Fig. 2 of the drawing, closing the apertures 23 and preventing fuel from passing from the reserve tank through the pipe 21 into the pipe 6 which leads to 105 the carburetor.

It will be obvious that as gasoline is sucked from the main fuel supply tank to the vacuum tank 2, a portion of the gasoline will be received through the T 13 into 110

the reserve tank, and since the connection of the same to the pipe 6 is normally closed, the reserve tank will continue to receive gasoline in this manner until the same is 5 filled, after which all of the gasoline sucked through the pipe 5 will pass into the vacuum tank.

Should the car run out of gasoline while 10 on the road, the reserve supply in the tank 10 7 may be conveyed by gravity through the pipe 21 into the pipe 6 to the carburetor by pulling the wire 26 outward until the lower 15 end of the tube 25 is raised above the apertures 23 in the tube 16, permitting the gasoline line in the reserve tank to pass through said 15 apertures into the tube 16 and thence to the carburetor as above described.

I claim:—

1. In combination with a fuel supply and 20 a carburetor, a vacuum tank, a continuous suction pipe connecting the fuel supply with the vacuum tank, a feed line connecting the vacuum tank with the carburetor, a reserve tank, a **T** in the top of the reserve tank 25 communicating with the suction pipe and an outlet in the reserve tank communicating with the feed line.

2. In combination with a fuel supply and 30 a carburetor, a vacuum tank, a continuous suction pipe connecting the fuel supply with the vacuum tank, a feed line connecting the vacuum tank with the carburetor, a reserve tank, a **T** in the top of the reserve tank 35 communicating with the suction pipe and an outlet in the reserve tank communicating

with the feed line, and means for normally closing the outlet.

3. In combination with a fuel supply and a carburetor, a vacuum tank, a continuous suction pipe connecting the fuel supply with the vacuum tank, a feed line connecting the vacuum tank with the carburetor, a reserve tank, a **T** in the top of the reserve tank 40 communicating with the suction pipe and an outlet in the reserve tank communicating with the feed line, means for normally closing the outlet, and means for manually opening the outlet.

4. In combination with a fuel supply and a carburetor, a vacuum tank, a continuous suction pipe connecting the fuel supply with the vacuum tank, a feed line connecting the vacuum tank with the carburetor, a reserve tank, a **T** in the top of the reserve tank 45 communicating with the suction pipe and an outlet in the reserve tank communicating with the feed line, a tube extending entirely through the reserve tank and connecting with the outlet and having an opening spaced from the bottom of the tank forming 50 a sediment trap, a tube slidably mounted through the first named tube, spring means for normally holding the second named tube in lowered position to cover said opening and a flexible wire connected to the second named tube for raising the same above said opening.

In testimony that I claim the above, I have hereunto subscribed my name.

JAMES A. SKAGGS.
